UNITED STATES PATENT OFFICE.

CHARLES RIGBY, OF CINCINNATI, OHIO.

SANITARY TOILET-SEAT.

1,296,220.

Specification of Letters Patent.

Patented Mar. 4, 1919.

Application filed November 8, 1916. Serial No. 130,194.

To all whom it may concern:

Be it known that I, CHARLES RIGBY, a citizen of the United States, residing at Cincinnati, in the county of Hamilton and 5 State of Ohio, have invented certain new and useful Improvements in Sanitary Toilet-Seats, of which the following is a specification.

My invention relates to toilet-seat protectors consisting of paper carried within a suitable container and adapted to have a portion of the paper drawn across the seat to form a sanitary covering, and has for its object the provision of novel clamping 15 means for holding the paper protector in position upon the seat.

A further object of my invention is to provide a clamping member so arranged and constructed that it may be attached to a 20 water-closet provided with a seat and a cover of standard construction, without interfering with the normal use of such parts, and also contemplates the use of a paper holder so positioned as to be comparatively 25 inconspicuous and out of the way.

The invention will be further readily understood from the following description and claims, and from the drawings, in which latter:

30 Figure 1 represents a plan view of a water-closet with its cover raised and partly broken away and with my sanitary protector secured thereto in position for use.

Fig. 2 is a front elevation of my improved 35 device.

Fig. 3 is a vertical transverse section on the line 3—3 of Fig. 1.

Fig. 4 is an elevation partially in vertical section taken on the line 4—4 of Fig. 1, the 40 clamping member being shown in dotted lines raised to its inoperative position.

Fig. 5 is an enlarged fragmentary view showing the details of the brake for the paper supply.

45 Fig. 6 is an enlarged view of a portion of the paper container and lid, showing the fastening means for the same; and,

Fig. 7 is a longitudinal vertical section on the line 7—7 of Fig. 2.

50 1 represents a water-closet bowl having a seat 2 pivoted thereto by hinges 3, which may also, if desired, pivotally support a cover 4 for the closet-seat, these parts being of standard or of any preferred construction.

A paper container 5 is secured at one side

of the closet-bowl by brackets 6, attached to the container adjacent each end thereof, and to the under side of the seat at the front and rear thereof respectively, the parts being 60 preferably so arranged that the top of the container 5 will lie in substantially the same plane as the top of the closet-seat, thereby placing the body of the container in a position where it will be out of the way, 65 but where access may be conveniently had thereto through its top.

The supply of sanitary paper is shown at 7, in the form of a roll, mounted upon a spindle 8 which is removably journaled in 70 brackets 9 secured to the opposite ends of the container. From the roll 7 the paper is fed through a slot 10 formed in the wall of the container which is nearest the closet-bowl, and thence over the top of the closet-seat to form a sanitary protective covering. 75 The lower edge of the slot 10 is provided with an outwardly extending curved lip 11 to prevent the paper being torn upon the edge of the slot, and a substantially wider lip or shelf 12 having an upwardly curved outer end 13 is provided at the upper edge of the slot 10, and at the level of the top of the container, to bridge the space between the container and the closet-seat, thus protecting the paper covering as it is drawn from the roll 7.

The lid 14 of the paper-container is hinged, as shown at 15, to the lip 12 at its junction with the rear wall of the container, 90 and is adapted to be held in closed position by a latch consisting of an apertured plate 16, provided at its lower edge with an outwardly extending lip 17 to be grasped by the fingers, and hinged to the edge of the lid 14, so that the aperture or socket may be forced over a rigid head or stud 18 upon the front wall of the container. The edges of the lid 14 are also provided with a downwardly extending flange 19 adapted to extend over the top edge of the container, thus 95 providing a dust and dirt proof receptacle.

A spring pressed brake 20 is adapted to press against the paper-roll 7 to hold the paper under the necessary tension as it is drawn from the container. This brake is exemplified as consisting of a sheet-metal plate 21 pivotally mounted upon a rod 22 secured by brackets 23 to the lower side of the lid of the paper-container, and adapted 100 to be forced downward into frictional engagement with the paper-roll by a spring 24

coiled upon the rod 22, and having one end 25 bearing against the lid of the container, and the other end 26 pressing against the plate 21. The free end of the plate 21 extends toward the free end of the lid 14, so that it can be readily grasped by the fingers when closing the lid, and thus held until the lid is almost entirely closed, to insure proper placing of the brake with relation to the paper.

After the paper-covering has been drawn from its container and over the seat, it is secured to the latter by a clamping member 27 comprising a flange 28 fitting over the edge of the seat, to clamp the paper between the seat and the flange, and also provided with a second flange 29 engaging the outer edge of the top of the seat to limit the downward movement of the clamp and aid in clamping the paper about the edge of the seat. This clamping member is hinged as shown at 30 to a plate 31, which is secured to the rear portion of the seat by screws 32, the various parts being so positioned that after the clamp has been swung to its closed or clamping position, the cover for the closet-seat may also be closed if desired.

The paper strip forming the sanitary cover is of a width sufficient to completely cover the seat, and is preferably perforated, as shown at 35, at suitable intervals in its length to form sections 36 for single seat-covers, and with perforations 33 in each seat-cover to form a removable portion 34, conforming to the opening in the seat, so that after the cover has been clamped in position, the central portion may be readily punched out along the line of the perforations. When it is desired to bring a new portion of the seat protector into use, the clamp 27 is raised, the paper cover is drawn forward until a new section is over the seat opening, and the clamp is then lowered to its operative position, firmly holding the cover in position, and the old section of the paper strip is torn off and destroyed, the removable portion of the newly placed section being removed along the line of perforations 33.

Copies of this patent may be obtained for five cents each, by addressing the "Commissioner of Patents, Washington, D. C."

Having thus fully described my invention, what I claim as new and desire to secure by Letters Patent, is:

1. The combination of a seat of the character described, a bracket secured to said seat and extending laterally solely at one side of said seat, a container for a flexible protective covering secured to said bracket, said container having an opening for said flexible protective covering presented toward said seat, and a pivoted clamp arranged to be received about the edge of said seat for clamping said flexible protective covering to said edge of said seat, and said container provided with a shelf above said opening, said shelf extending laterally over the position of said flexible protective covering and said bracket to a point proximate to the path of said pivoted clamp.

2. In a sanitary toilet seat, the combination of a seat-body having an opening, a sheet of protective sanitary paper arranged to be received upon said seat-body in direct contact therewith, and a clamp provided with a downwardly extending flange fitting about the outer peripheral edge of said seat-body and with an inwardly extending flange limiting downward movement of said clamp, said clamp contacting said sheet of said protective sanitary paper, and said seat-body extending inwardly to a substantial extent beyond said last-named flange for forming a substantially wide resting surface for the user between the wall of said opening and said clamp, and constructed and arranged whereby a single thickness of protective sanitary paper is clamped between the outer edge of said seat-body at one face of said paper and said clamp at the other face of said paper with the inner edge of said protective sanitary paper received over the wall of said opening.

In testimony whereof, I have hereunto signed my name in the presence of two subscribing witnesses.

CHARLES RIGBY.
